UNITED STATES PATENT OFFICE.

JAMES L. SOWERS, OF MUNCIE, INDIANA, ASSIGNOR TO THE TYLER MANUFACTURING COMPANY, OF MUNCIE, INDIANA, A CORPORATION OF INDIANA.

FRUIT AND VEGETABLE PRESS.

Application filed April 17, 1925. Serial No. 23,959.

This invention relates to improvements in vegetable and fruit presses or sieves of that type which comprises a perforated cone shaped receptacle, mounted on a stand, and in conjunction with which said receptacle, there is provided a coneshaped crusher which is adapted to be rotated on its axis and revolved within the said receptacle, the function of said crusher being to crush and force the plastic or semiplastic receptacle contents through the perforations thereof.

This type of press is of especial utility as a household device, a practicable size for the receptacle being about seven inches in width, and the stand being about nine inches high.

Advantages desirable in a device of the kind referred to are, that the contents of the receptacle may be crushed effectively and with a minimum of exertion, and that there may be no undue strain or wear upon any of the parts of the device.

My invention contemplates the providing of a cone-shaped perforate receptacle having outwardly molded annular shoulder and vertically or substantially vertically disposed neck, the said neck being adapted for engagement and retention by a support stand or holder, and a cone shaped crusher element having an annular shoulder adapted to roll on the annular shoulder of the receptacle, the length of the said crusher element, from its shoulder to the point thereof, being slightly less than the distance from the shoulder or bearing race of the receptacle to the apex of the receptacle. By this combination and arrangement of parts, the plastic contents are prevented from rising above the shoulder of the receptacle, and at the same time there is a rolling or crushing contact maintained throughout the length of the body of the crusher, without undue strain on the receptacle walls of the apex thereof, and without tendency of the contents to become massed or impacted in the apex portion of the receptacle.

The objects of my invention are accomplished by, and the invention is embodied in the new, construction and arrangement of parts described in the following specification, defined in the appended claims, and illustrated in the accompanying drawings.

The several parts of the device are identified by suitable characters of reference applied thereto.

Figure 1 is a side view of my improved vegetable and fruit press.

Figure 2 is a top plan view of Figure 1.

Figure 3 is a top plan view on the line 3—3 in Figure 1, the receptacle having been removed.

Figure 4 is an enlarged vertical sectional view taken on the line 4—4 in Figure 2.

The cone shaped receptacle A is made of perforated sheet metal, the neck A¹ thereof being of vertical formation and providing the annular shoulder offset A² which is curved in cross section, as plainly shown in Figure 4. A frame ring B is curved in cross section and has a double lipped flange B¹ between whose sides is securely retained the lip or flange of the neck of the receptacle.

Adapted to be rolled within said receptacle, is a cone shaped crusher C. This crusher may be made of hard wood such as maple or elm, and is of such formation relative to the parts of the device hereinbefore described, that when its point is at lowered position in the receptacle, its shoulder C¹ and shoulder C², are in rolling engagement with the offset A² of the neck, and with the underside of the frame ring B respectively. By this form and combination of the parts described there is no tendency of the crusher to impact any contents in the apex of the receptacle, and the effect of the crusher, in its motion with its shoulder C¹ rolling on the shoulder A² and its lower end being free, is, that the pressure of the plastic contents against the wall of the receptacle, is practically uniform throughout. Moreover there is no pressure or strain of the metal at the point of the receptacle.

The neck and head portion of the crusher may be formed integral with the body portion of the structure, as shown, or may be of swivel or pivoted construction. The integral form of head has been found satisfactory and is to be preferred on account of its being economical of construction.

The receptacle constructed in accordance with my invention is especially adapted to being held in secure position on a support stand of any suitable structure in which is embodied a band or frame piece which is adapted to embrace the neck of the receptacle. A support frame of desirable form and structure is that shown in the drawings.

and it consists of a resilient metal bar D its body portion being curled to circular form shown in Figure 3; the end portions are turned outwardly thence are brought to positions spaced apart and their ends are secured together; thus forming a handle E. Uprights F, G and H, also made of flat metal bars, are riveted at their tops to the said clamp band D, and are retained spaced 10 apart at their lower portions by a spider member having the arms K, and a central ring portion L.

The inner surface of the clamp member may be plain or serrated, the latter form 15 of surface being preferred as contributory to the tenacity of the engagement between the receptacle neck and the said clamp member.

To separate the receptacle from the stand 20 the operator's grip is simply released at the handle E, the receptacle in its entirety may then be simply lifted free from the stand.

A fruit and vegetable press constructed in accordance with my invention is compact in size, light in weight, easy to use, and economical of manufacture. The receptacle being easily removable from the stand, the entire device is capable of being easily 25 and thoroughly cleansed and maintained in sanitary condition.

What I claim as my invention, and desire to secure by Letters Patent, is:—

1. A device of the kind described, comprising an inverted cone-shaped perforate 30 receptacle having outwardly molded shoulder and neck, the latter being adapted for retention by a support stand, and a cone-

shaped crusher having an annular shoulder which is adapted to roll on the shoulder of said receptacle. 40

2. A device of the kind described, comprising an inverted conical perforate receptacle having outwardly molded shoulder and neck, the latter being adapted for retention by a support device, and a cone shaped crusher provided with an annular shoulder which is adapted to roll on the shoulder of the receptacle, the dimension of the crusher from its shoulder being such that the point of the crusher occupies position 50 removed from the apex of the receptacle.

3. A device of the kind described, comprising a conical perforate receptacle having outwardly molded shoulder and neck, and a cone shaped crusher having an annular shoulder adapted to roll on the shoulder 55 of the receptacle.

4. A conical perforate receptacle for a device of the kind described, having an outwardly molded annular shoulder adapted to 60 constitute a race or offset upon which the shoulder of the cone shaped crusher may be rolled, and having an integrally formed neck adapted for retention by a support device. 65

5. A conical perforate receptacle for a device of the kind described, having an outwardly disposed annular shoulder or race and an integrally formed vertical neck provided with outwardly disposed annular lip, 70 and an annular head ring provided with an outwardly disposed flange in which the lip of the receptacle is secured.

JAMES L. SOWERS.
